UNITED STATES PATENT OFFICE.

FREDERICK PHILIPPI, OF ST. LOUIS, MISSOURI.

WATER GAGE AND INDICATOR.

SPECIFICATION forming part of Letters Patent No. 653,755, dated July 17, 1900.

Application filed December 30, 1899. Serial No. 742,108. (No model.)

To all whom it may concern:

Be it known that I, FREDERICK PHILIPPI, a citizen of the United States, residing at the city of St. Louis, State of Missouri, have invented a certain new and useful Improvement in Water Gages and Indicators, of which the following is a full, clear, and exact description, such as will enable others skilled in the art to which it appertains to make and use the same, reference being had to the accompanying drawings, forming part of this specification.

This invention relates to a new and useful improvement in a liquid-gage, and is designed particularly for indicating the amount of water or other liquid contained in a vessel when it is otherwise impossible or inconvenient to determine the same.

The object of this invention is to enable a person to ascertain the amount of water or other liquid contained in a vessel which is either too high up or too low down to permit of an ordinary glass gage to be efficiently employed—as, for instance, in water-tube boilers the main boiler or shell is located extraordinarily high—say twelve feet, more or less, above the ground-level—and if this boiler were equipped with an ordinary glass-tube gage, which must necessarily be some little distance higher than the water-level in the boiler, it would be difficult for a person standing on the ground to accurately tell just what the gage indicated. Furthermore, glass gages are objectionable in that they frequently become broken or cracked or discolored by muddy water, which renders them inefficient and difficult to read. These objections are all overcome by the use of my invention, and the object sought is accomplished in my invention by the mechanism employed in the accompanying drawings, in which—

Figure 1 is a conventional illustration in front elevation, parts being broken away and parts shown in section, of a portion of a boiler or other vessel, showing my improved gage in proper position relative thereto, and a diagrammatic illustration of an audible signal and its operating-battery in connection therewith. Fig. 2 is an enlarged front elevational view of the gage proper. Fig. 3 is a rear elevational view of the gage proper with its cap

removed and a portion of the casing being broken away and a portion shown in section to more clearly illustrate the invention. Fig. 4 is a vertical sectional view of the gage proper, taken on the line 4-4 of Fig. 3; and Fig. 5 is a plan view, partly in section, of the gage proper.

Similar characters designate similar parts throughout the several views.

In the drawings, A represents a vessel—such, for instance, as a steam-boiler—which contains a quantity of water or other liquid, and B an auxiliary reservoir or pipe arranged in juxtaposition thereto and connected therewith at its lower end by a pipe a. This reservoir or pipe B is provided upon its extreme lower end with a cap-piece b, and to said cap-piece and in communication with the interior of said reservoir is secured one end of a pipe C. Secured to the lower end of this pipe C is a casting D, which casting consists, briefly, of a vertical cylindrical portion d, formed with an axial bore d', and extending laterally from this cylindrical portion is a disk-shaped portion d'', which disk-shaped portion has formed in its front and rear faces recesses d''' and d''', respectively, or, in other words, this disk-shaped portion d'' is provided with recesses d''' and d''', separated from each other by a web or partition d⁵. The recess d''' is caused to communicate with the bore d', which communication forms an elongated slot d⁶, and through this slot protrudes one portion of the rim of a spur-gear E, located concentrically with the recess d'''.

F represents a bushing screwed or otherwise fastened in a suitable perforation formed in the center of the web or partition d⁵, the purpose of which is to serve as a bearing for the arbor e of the spur-gear E and at the same time form one portion of a stuffing-box in order that said arbor will be effectually packed.

Formed on one side of the spur-gear E is an axially-protruding boss e', which is bored from the inside face of the spur-gear to a point near its outer end, and secured to this boss and projecting inwardly therethrough is the arbor e, said arbor being sufficiently long to pass through its bushing and extend sufficiently far into the recess d''' to receive a hand or index-finger G and a nut G', which is preferably screwed thereon.

The bushing F is provided with an outwardly-extending nose f, and when the spur-gear is in its proper position and its arbor is passed through the perforation in said bushing said nose f enters the recess formed in the boss e' and rests against a suitable packing e'', located in the recess in said boss and around the arbor.

H represents a cap-piece which covers the recess d''' by being fastened to the casting D by screws, and formed in the center of this cap-piece is a screw-threaded orifice which receives a screw h, said orifice and its screw being in axial alinement with the boss e' of the spur-gear G. Said screw h is permitted, when desirable, to rest upon or against said boss and force the spur-gear toward the web or partition d⁵. This action forces the packing around the arbor in the recess against the end of the nose f and effectually packs the arbor and prevents leakage of water thereby. This screw h is provided with a jam-nut h', which impinges against the outer face of the cap-piece H and performs the double function of first locking the screw h in a given position and, second, in serving as a binding-post for an electric wire and conductor 2.

Located in the bore d', passing through the slot d⁶ and secured to the web or partition d⁵, is a guide-piece I, the outer end of which, or that portion which is located in the bore d', is provided with a suitable U-shaped or hook-like portion i, and between the parallel members of this U-shaped portion is arranged a rack-bar J, which is designed to pass slidably therebetween. This rack-bar is so arranged that its teeth mesh with the spur-gear E and will upon longitudinal movement of said rack rotate said gear.

K represents a ring made of any suitable insulation material—such, for instance, as vulcanized rubber or fiber—which is arranged in the recess d''', and within this insulation-ring and secured thereto is a metallic ring L, formed with a plurality of preferably equally distant screw-threaded perforations l, and into one of these perforations is threaded one end of a binding-post screw M, which binding-post is arranged outside of the material surrounding the recess d''', but insulated therefrom by a bushing m, and secured to said binding-post is an electric conductor or wire 3. Thus it will be seen that the ring L is a terminal of an electric circuit.

N represents a suitable leaf-spring which is secured to a block n, which in turn is secured to the ring L by having a screw n' pass therethrough and into one of the plurality of perforations l.

Secured to the longer end of the hand or index-finger G is a thin leaf-spring g, the same being so arranged and proportioned that when the hand moves around or makes a whole or part of a revolution, depending upon the location of the spring N, said spring g will contact with said spring N and complete an electric circuit through the battery O, the mag-

nets of the bell P, wire 2, the casing or casting D, the hand G, spring g, spring N, ring L, binding-post M, and wire 3, and effect an audible signal of said bell P.

Q indicates a float, preferably in the form of a hollow sphere, which is arranged in and designed to float upon the water or other liquid contained in the reservoir or pipe B, and secured to the lower portion of this float is a rod R, which rod passes downwardly through the liquid in the reservoir or pipe B into and through the pipe C, and has its lower end attached to the upper end of the rack-bar J, which rack-bar is arranged partially in said pipe C and partially in the bore d' of the casting D, and, as before stated, is in mesh with the spur-gear E, contained in said casing or casting D.

S indicates a suitable length of pipe screwed or otherwise secured to the lower end of the cylindrical portion d of the casting D and is in communication with the bore d'. Arranged on the lower end of this pipe S is a petcock T, the purpose of which is to drain or draw off the water or other liquid from the pipe S, bore d', recess d''', pipe C, and the reservoir or pipe B when desired and for obvious reasons.

The operation of the device just described is as follows: When water or other liquid is admitted to the boiler or other vessel A, said water or other liquid will rise in the reservoir or pipe B, the same being admitted thereto through the pipe a, and causes the float Q and its carried rod R and the rack-bar J to likewise rise, which action causes the spur-gear E and its controlled index finger or hand G to rotate, which movement will continue until the desired amount of water or other liquid has been admitted to the vessel A, which amount, we will assume, is just sufficient to bring the index finger or hand to a given point on the dial of the indicator, after which the admission of water to said vessel is discontinued. When the water or other liquid contained in the vessel A is drawn therefrom either directly or by evaporation—such, for instance, as the formation of steam—the level of the liquid is obviously lower, which action causes the float Q and its carried rod R and the rack-bar J to descend and rotate the spur-gear E, which rotation causes the hand or index-finger G to move in the proper direction to indicate on the dial of casting D the amount of water or other liquid thus drawn from the vessel A. As the water or other liquid continues to be drawn from vessel A the index finger or hand G continues to move toward the leaf-spring N, which, as before explained, is a terminal of an electric circuit, and when the water or other liquid becomes so low in the vessel A that it is desirable for an attendant to be apprised of the fact the hand G will have moved sufficiently far to have caused its carried leaf-spring g, which is the other terminal of the electric circuit, to contact with said spring or terminal N and complete said elec-

tric circuit and cause the bell P to ring, thus notifying the attendant of the fact that said water or other liquid is as low in the vessel A as it is desirable to have it, whereupon he will 5 proceed to admit more water or other liquid to said vessel.

By the construction of my device it will be seen that all of the moving parts of my device, with the exception of the index finger 10 or hand, is submerged in the water or other liquid and by which arrangement of the parts the same are constantly lubricated as well as being effectually housed and away from dust or objectionable matter. It will also be ob- 15 served that by making the arbor of the spur-gear quite small in diameter it is quite easily packed or made water-tight, and friction is also to a great extent eliminated.

When the packing of the arbor becomes in- 20 efficient in the course of time, I am enabled to readily tighten the same by simply turning the screw h in the proper direction, as is ob- 25 visible.

It will be observed from a glance at the 25 drawings that I am enabled to so arrange the parts that the variation between the maximum and minimum amount of water which it is desired to have in a vessel will be indicated, and I am enabled to adjust this device 30 to suit different conditions in different-sized vessels by a slight adjustment of the parts. To indicate the maximum amount of water that a vessel should contain, I first fill said vessel with the desired amount of water and 35 then set the index-hand on the proper point on the dial by the manipulation of the nut G', and to sound an audible signal and indicate the minimum amount of water it is desired to have in the vessel I adjust the position of the spring N by securing it in any one 40 of the perforations l on the ring L, as will be readily understood.

I am aware that minor changes can be made in the construction, arrangement, and combination of the several parts of my device without in the least departing from the nature and principle of my invention, and, furthermore, I wish it understood that I do not confine myself to the arrangement of the parts 50 wherein the vessel containing the water or liquid must be above the gage and indicator, for the reason that the device would work equally as well if the pipe C and its carried parts were made to rise from the top of the 55 reservoir or pipe B, as would be a desirable construction were the vessel A arranged in a pit below the floor or ground level.

Having thus described my invention, what I claim, and desire to secure by Letters Patent, is—

1. In combination with a reservoir containing a liquid, of a float arranged therein, a rack-bar connected to said float and movable therewith, a gear in mesh with said rack-bar 65 and capable of making a complete revolution, a housing for inclosing said parts, a spindle on which said gear is mounted, said spindle

extending outside of the housing, an indicating-hand mounted on the outer end of said spindle and forming one terminal of an electric circuit, a single contact-point in the path of said indicating-hand, said contact-point being the other terminal of an electric circuit, whereby, when the level of the liquid in the reservoir rises and falls, the float causes 70 the gear-wheel to rotate in one direction or the other, and the indicating-hand carried thereby contacts with the single fixed contact-point at the "high-water" mark, and when the level of the liquid falls, the gear is rotated reversely to make a complete revolution, the indicating-hand engages the same single contact to complete the electric circuit when the "low-water" level is reached, and a signal in said circuit which is operated 75 when the indicating-hand completes the circuit through the single stationary contact at both the "high" and "low" water levels; substantially as described.

2. In combination with a suitable casing 90 having a bore d' formed therein, of a rack-bar arranged in said bore, said casing being also provided with a recess d''' which opens into said bore d', a spur-gear arranged in said recess, and in mesh with said rack-bar, a cap-piece for covering said recess, a guide for said rack-bar, an arbor for said spur-gear, a journal for said arbor, means for packing said arbor to prevent liquid from passing between said arbor and its journal, and an index finger or hand arranged on said arbor and outside of the recess in which said spur-gear is arranged; substantially as described.

3. In combination with a suitable casing 105 having a bore d' formed therein, of a rack-bar arranged in said bore, said casing being also provided with a recess d''' which opens into said bore d', a spur-gear arranged in said recess, and in mesh with said rack-bar, a cap-piece for covering said recess, a guide for said 110 rack-bar, an arbor for said spur-gear, a journal for said arbor, means for packing said arbor to prevent liquid from passing between said arbor and its journal, said casing being also provided with a recess d''' arranged in 115 the opposite side of the casing to that in which the first-mentioned recess d''' is formed, a ring of insulation material arranged in said recess d''', a metallic ring arranged on said insulation-ring, said metallic ring being provided with a plurality of perforations, a leaf-spring which is secured to said metallic rings through the instrumentality of a pin or screw which is designed to enter one of the plurality of perforations, an electric conductor connected to said metallic ring, an index finger or hand arranged on the arbor of said spur-gear, and an electric conductor connected to said hand or index-finger; substantially as 125 and for the purpose specified.

4. In combination with a casing formed with two axially-disposed recesses d''' and d'' which are separated from each other by a web or partition d⁵, said casing being also pro- 130

vided with a bore d' arranged at an angle to the axis of said recesses d'' and d''' , and communicating with the latter, of a rack-bar arranged in the bore d' , a spur-gear arranged 5 in the recess d''' , and in mesh with said rack-bar, an arbor for said spur-gear, said arbor being journaled in, and caused to project beyond the web or partition d^5 , and into the recess d'' , a cap-piece for covering the recess d''' , means for packing the arbor of said spur-gear in order that liquid may not pass between said arbor and its journal, a hand or index-finger arranged on said arbor and located within the recess d''' , a ring of insulation material arranged in said recess d''' , a 10 metallic ring arranged on said insulation-ring, 15

a metallic device arranged on said metallic ring, and projecting therefrom, and designed to be touched by the longer end of the index-finger, means for adjusting said metallic device on said metallic ring, an electric conductor secured to said metallic ring, and a metallic conductor secured to the casing; substantially as and for the purpose specified. 20

In testimony whereof I hereunto affix my 25 signature, in the presence of two witnesses, this 26th day of December, 1899.

FREDERICK PHILIPPI.
